UNITED STATES PATENT OFFICE.

PAUL KESTNER, OF PARIS, FRANCE.

APPARATUS FOR ENABLING EXTRACTS, INFUSIONS, OR DECOCTIONS TO BE OBTAINED IN A CONTINUOUS MANNER.

1,325,298.

Specification of Letters Patent. Patented Dec. 16, 1919.

Application filed February 11, 1919. Serial No. 276,336.

To all whom it may concern:

Be it known that I, PAUL KESTNER, citizen of the French Republic, residing at Paris, Department of the Seine, in France, 5 and whose post-office address is 34 Rue de Chateaudun, in the said city, have invented certain new and useful Improvements in Apparatus for Enabling Extracts, Infusions, or Decoctions to be Obtained in a 10 Continuous Manner; and I do hereby declare the following to be a full, clear, and exact description of the invention, such as will enable others skilled in the art to which it appertains to make and use the same.

15 This invention has reference to apparatus for enabling extracts, infusions or decoctions to be obtained in a continuous manner.

20 My invention consists in an apparatus in which the solvent and the material from which an extract, infusion or decoction, is to be obtained, are made to travel in relatively opposite directions, the solvent becoming richer in or more and more impregnated with the principles or qualities of the 25 substance acted on whereas fresh material is constantly supplied to replace that which has become exhausted.

25 A very useful purpose to which my invention may be applied is the dissolving out the sugary extractive contained in beets and in the accompanying drawing I have illustrated—merely by way of example—an apparatus suited to that purpose. I wish it, however to be understood that my invention 30 is not limited in its scope or application to the aforesaid purpose as it may be equally well employed in obtaining extracts, infusions or decoctions from other materials, for example—to mention only two—Peruvian bark and logwood.

The material will be comminuted by any usual and appropriate method to facilitate the solution of the extractive it contains.

In the preferred constructional form of 45 my invention the apparatus comprises a series of buckets having perforated bottoms in which is placed the comminuted material. These buckets are moved slowly upward in a quasi column and into, the for 50 the time being uppermost bucket of the column, water or other solvent is poured.

The material thus steeped in water in the said uppermost bucket will give up some of its extractive and the water will pass through 55 the perforations to the bucket immediately

below and there absorb or take up extractive from the material contained therein. The water thus passing through the whole series of buckets constituting the column will become increasingly rich.

Such a preferred constructional form of 60 my invention is illustrated diagrammatically in side elevation in Figure 1 of the accompanying drawing, Fig. 2 being a sectional left hand view on line A, B of Fig. 1. 65

The apparatus as regards its essential members comprises a series of cylindrical buckets 1, having perforated bottoms and carried between two endless chains 2 by trunnions 3. The latter are provided with 70 pinions 4 (one on each end) so that the bucket may be caused to tilt or even to make a complete rotation by the pinions engaging a rack or equivalent of proper 75 length.

The chains 2 are supported and driven by two toothed wheels 6 and at their lower ends said chains pass over a pair of loose 80 wheels 8, a suitable motor and its transmission gear 5 imparting slow rotary movement to the wheels 6 in the direction of the arrow 7. It will be seen therefore that on the left hand side of Fig. 1, there is a column of slowly ascending buckets into which successively the material—for example comminuted beet—is delivered from a hopper 10 through a chute 11. Each bucket as it approaches the chute will be tilted—as shown at 1^a—by the engagement, on passing, of its toothed wheel or wheels 4 with a tooth or rack 9. Thus inclining or tilting each bucket enables it the better to receive the material from the chute.

At or near to the top of the apparatus 85 is a water or other solvent supply pipe 15 which in the example illustrated is in connection with a tank or cistern 14.

Said pipe supplies water to the uppermost bucket of the column and this passes 90 through the perforations to the next bucket below it and so on through the whole series of buckets.

In its passage through all the buckets of the column it will dissolve out some of the extractive contained in the material in 105 each bucket and will thus be more or less gradually enriched until finally it is received in a vat 16 to be thereafter dealt with in any desired manner.

The material will be more and more de- 110

pleted or exhausted of its extractive as the buckets reach nearer to the top of the column and it is to be considered desirable to make the apparatus of such dimensions as to the 5 number of buckets contained in the column and speed of movement, etc., that the material will practically have had all its extractive dissolved out before the for the time being uppermost bucket of the column moves 10 to the position marked 1^b.

Simultaneously with the uppermost bucket moving away from the column of buckets with the exhausted matter, a bucket will at 15 the bottom of the column be brought into line and be supplied with fresh material as described.

As the bucket at 1^b continues to move toward the right its pinions 4 will engage with racks 12 of such length that the bucket 20 will first be completely reversed—to thereby empty it of the exhausted matter—and then to bring it back to its normal position without strain. The material thus discharged is received in a hopper 13 and by 25 a chute 14 is conducted away.

Instead of charging the buckets at the bottom of the ascending column they might be charged for example at the top of the descending column which would have the 30 advantage that the two columns of buckets—all the latter charged with material—would more or less better balance each other.

If desired the ascending column of buckets may be surrounded by a casing 18 to pre-

vent cooling of the contents and adapted, if 35 desired of having steam or hot air injected into it to impart heat to or to maintain the heat of the contents of the buckets. Or any other suitable means may be provided for heating and for maintaining the heat of the 40 contents of the buckets.

A tank 17 may be provided to receive drippings from the descending buckets.

I claim:

1. Apparatus of the class described comprising a continuous series of containers, means for supplying material to be treated, successively, to the containers at the lower end of one reach of the series, means for supplying a solvent, successively, to the containers at the upper end of said reach and means for positively rotating the containers after the application of the solvent to the material within the containers. 45

2. Apparatus of the class described comprising a series of containers having perforated bottoms, means for supplying the containers with material to be treated at the lower end of the series, means for supplying the containers with a solvent at the 50 upper end of the series, and means for moving the series of containers upwardly vertically whereby the solvent will pass, successively, through the containers from the upper to the lower end of the series. 55

In testimony whereof I affix my signature.

PAUL KESTNER.
